DISPENSING NOZZLE FOR A PRESSURIZED CONTAINER

Peter P. Gach, Evansville, Ind., assignor to Sunbeam Plastics Corporation, Evansville, Ind., a corporation of Indiana

Filed Nov. 17, 1969, Ser. No. 20,120

Term of patent 14 years

Int. Cl. D9—02

U.S. Cl. D9—258

FIG. 1-

FIG. 2-

FIG. 3-

FIG. 4-

FIG. 5-

FIG. 6-

FIG. 1 is a plan view of a dispensing nozzle for a pressurized container embodying my new design;

FIG. 2 is a front view in elevation taken from the position indicated by the line 2—2 of FIG. 1;

FIG. 3 is a side view in elevation taken from the position indicated by the line 3—3 of FIG. 1;

FIG. 4 is a rear view in elevation taken from the position indicated by the line 4—4 of FIG. 1;

FIG. 5 is a bottom view; and

FIG. 6 is a view in perspective, shown on an enlarged scale of the dispensing nozzle for a pressurized container illustrated in FIGS. 1—5.

I claim:

The ornamental design for a dispensing nozzle for a pressurized container, as shown.
